UNITED STATES PATENT OFFICE.

JESSE H. KEYSE, OF DENVER, COLORADO.

AUXILIARY TRIGGER FOR GUNS.

No. 851,626.

Specification of Letters Patent.

Patented April 23, 1907.

Application filed January 8, 1907. Serial No. 351,342.

To all whom it may concern:

Be it known that I, JESSE H. KEYSE, a citizen of the United States, residing at the city and county of Denver and State of Colorado, have invented certain new and useful Improvements in Auxiliary Triggers for Guns; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in auxiliary triggers for double barrel guns.

As is well known the triggers used in connection with the respective barrels of the gun, are arranged one in advance of the other. 20 This necessitates that after pulling one trigger, a considerable movement of the hand is required in order to pull the other trigger. Moreover while pulling the forward trigger the second finger or that next to the trigger 25 finger is pressed so tightly against the guard that the recoil of the gun acts injuriously thereon, to such an extent that after this trigger has been pulled a considerable number of times during a short interval as in trap shooting, the recoil of the gun incident to the corresponding discharges or explosions, produces very painful consequences, the said second finger being very badly bruised. Furthermore it often happens while shooting 30 game in the open field, that it becomes necessary to discharge two barrels of the gun in very rapid succession; and this becomes practicable in consequence of the aforesaid arrangement of the two triggers, since the 35 one is so far in advance of the other, that an appreciable period of time must elapse while moving the hand sufficiently to allow the trigger finger to pass from the one trigger to the other. During this time a bird on the 40 wing will have time to fly a considerable distance.

The object of my improvement is to overcome all of these difficulties, and it consists in providing the forward trigger of the gun 45 with an auxiliary trigger or member which extends rearwardly such a distance as to be very nearly in lateral alinement with the rear trigger, the auxiliary trigger and the rear trigger being so close together, that after 50 pulling the auxiliary member, only a slight movement of the end of the trigger finger

forward of the first joint, is required in order to pull the other trigger. This auxiliary trigger member may be detachably connected with the forward trigger or formed integral therewith as may be desired. 60

Having briefly outlined my improved construction as well as the function it is intended to perform, I will proceed to describe the same in detail reference being made to the accompanying drawing in which is illustrated an embodiment thereof.

In this drawing, Figure 1 is a fragmentary side elevation of a double barrel gun showing the forward trigger equipped with my improvement. Fig. 2 is an underneath view of the same with the trigger guard removed, its position, however, being indicated by dotted lines. Fig. 3 is a detail elevation of my improved auxiliary trigger member 70 viewed from the side opposite that shown in Fig. 1. Fig. 4 is a top plan view of the same. Fig. 5 is a view showing the auxiliary trigger member formed integral with the forward trigger. 75

80 The same reference characters indicate the same parts in all the views.

Let the numeral 5 designate a trigger guard attached to the stock or body of the gun 6 in the usual manner. The forward trigger 7 85 and the rear trigger 8 are shown in the drawing arranged in the ordinary way. Referring first to Figs. 1 to 4 inclusive, to the forward trigger is attached an auxiliary trigger member 9 the said member being provided 90 with a suitable clamping device 10 consisting of a member 12 hinged to a lug 13 at one extremity, while its other extremity is slotted to receive a clamping bolt 14 pivotally connected with a trigger lug 15, whereby the 95 bolt may be disengaged from the part 12 or thrown to the dotted line position in Fig. 4. To this clamping bolt is attached a thumbnut 16. By adjusting this nut it is evident that the auxiliary trigger member may be securely clamped to the forward trigger 7 as 100 shown in Figs. 1 and 2.

In the form of construction shown in Fig. 5 the auxiliary trigger member designated 7^A is formed integral with the forward trigger. 105

Whichever form of construction is used, the auxiliary trigger member may be shaped as desired in order to give the results stated. As shown in the drawing this trigger member is hook-shaped or fashioned or shaped somewhat similar to the ordinary trigger. The rear part of the auxiliary trigger member 110

occupies a position only slightly in advance of the curved or hook-shaped rear portion of the rear trigger 8. Hence in using the gun the auxiliary trigger member will be pressed when it is desired to operate the forward trigger. As soon as this is done, a slight movement only of the end of the trigger finger, is necessary in order to press the rear trigger. Hence the two barrels of the gun may be fired in more rapid succession than is possible when using the ordinary trigger construction. Moreover the position of the auxiliary trigger member is such that it is never necessary to press the second finger against the trigger guard while operating the forward trigger.

The auxiliary trigger member is provided with an upward projection or extension 9^A whereby it is adapted to engage the stock or trigger plate of the gun above the guard which forms a stop to prevent further movement. This stop feature prevents the movement of the auxiliary trigger member far enough to allow the trigger finger to act on the rear trigger 8.

Having thus described my invention, what I claim is:

1. The combination with the rear trigger of a double barrel gun, of a forward trigger whose finger piece is provided with a rear-³⁰ wardly extending auxiliary finger piece.
2. The combination with the forward and rear triggers of a double barrel gun, of an auxiliary finger piece detachably connected with the finger piece of the forward trigger, ³⁵ and extending rearwardly from the latter, substantially as described.
3. The combination with the forward and rear triggers of a double barrel gun, of an auxiliary trigger or finger piece attached to ⁴⁰ the finger piece of the forward trigger, extending rearwardly from the latter and terminating at a point slightly in advance of the finger piece of the rear trigger.

In testimony whereof I affix my signature ⁴⁵ in presence of two witnesses.

JESSE H. KEYSE.
